UNITED STATES PATENT OFFICE

RAYMOND GARES, OF KANKAKEE, ILLINOIS

CARPENTER'S RULE

Application filed September 4, 1928. Serial No. 303,835.

My invention is an improvement in carpenters' rules, and relates more especially to that particular type comprising a plurality of sections pivoted one to another so that 5 the several sections constituting the rule may be folded together laterally and occupy comparatively small space, such rules being commonly known as zigzag rules.

The primary object of my invention is to 10 provide an attachment for a carpenter's rule of this special type consisting of an auxiliary jointed rule having a metal clip pivoted thereto whereby said auxiliary rule can be readily attached to any one of the main sections of the carpenter's rule when the latter 15 is extended to thereby permit the mechanic to obtain inside measurements quickly and accurately.

A further object of my invention is to 20 provide an attachment of this kind which is adapted to be connected to the zigzag rule when folded without materially increasing the bulk thereof, being arranged in association therewith as to practically form a continuation of said folded rule for compactness in placing the complete measuring rule 25 in the mechanic's kit.

A further object of my invention is to 30 provide an attachment for a carpenter's rule which is simple in construction, can be manufactured at a small cost, and may be connected to any one of the jointed sections of the rule according to the location of the measurements required, as well as closely arranged at one side of the zigzag rule when 35 folded.

With these principal objects in view my invention consists in a rule attachment having plates pivoted thereto and slidable one 40 on the other with flanges or projections for engaging opposite sides of the rule, and a spring for normally operating the sliding plate to engage said rule; all as hereinafter fully described and specifically set forth in 45 the appended claims.

In the drawings

Figure 1 is a side elevation of the zigzag rule in closed arrangement with the auxiliary rule-section thereon.

Fig. 2 is a plan view of Fig. 1.

Fig. 3 is a side elevation showing the auxiliary rule-section attached to one of the sections of the main rule.

Fig. 4 is an enlarged detail view of one of the plates of the metal clip. 55

Fig. 5 is a similar view of the other plate.

Fig. 6 is a vertical sectional view of the clip showing the same attached to the auxiliary rule-section; and

Fig. 7 is a transverse sectional view. 60

As shown in the drawings the auxiliary rule-section constructed in accordance with my invention is particularly applied to that form of carpenter's rule commonly known as a zigzag rule although of course it will 65 be understood that the same may be applied to any other form of carpenter's rule or similar measuring device. As usual in the construction of a carpenter's rule of the type shown the several sections thereof designated 10 are connected one to another by pivot joints 11, and for the purpose of forming a compact device to occupy a small amount of space in the mechanic's kit when my invention is applied to a carpenter's 70 rule one end section 12 of the zig zag rule is reduced in length and the end section 13 of the auxiliary rule is also reduced in length to join with the aforesaid short section of the zigzag rule when said auxiliary rule is 75 folded and placed thereon as shown in Fig. 1. The auxiliary rule is preferably made up of two jointed sections 13 and 14, and to the outer end of the longer section 14 there is attached a metal clip 15 by means of a 80 pivot pin 16, said metal clip comprising an inner plate 17 and an outer plate 18 slidable laterally one upon the other for which purpose the plate 17 is provided with a slot 19 while the companion plate 18 is provided with an opening 20 corresponding with the size of the pivot pin which passes through the opening and slot from the auxiliary rule. One end of the pivot-pin is upset on plate 17 85 and the other end formed with a head bearing against the section of the auxiliary rule and the other end formed with a head bearing against the section of the auxiliary rule 90 to which the clip is connected, as shown in Fig. 6. For the purpose of attachment to the carpenter's rule the inner plate 17 of the clip carried by the auxiliary rule is provided 95

100

at one side with outwardly projecting short flanges 21 21 and opposed to these flanges the outer plate is provided with an outwardly projecting flange 22, a section of the zigzag rule being clamped between these flanges, and in order that the slideable plate may be spring-actuated to engage said rule-section it is provided at the outer end of an extension of one side thereof with an outwardly projecting flange 23 to which is attached a flat spring 24 the free ends of which bear against the flange 22 of the companion plate, and to provide for manipulating the slideable plate against the action of the spring the outer plate has a reduced extension 25 projecting between the flanges 21 21 of plate 17 at the outer end of which is an outwardly turned flange or finger engaging portion 26 cooperating with the flange or finger engaging portion 23 whereby the slideable plate may be manipulated against the action of the spring to release the clip from the carpenter's rule by pressure against the flanges 23 and 26, as will be understood by reference to Fig. 6. From the foregoing description it will be obvious that the companion plates forming the metal clip are rotatable on the pivot pin, and that one of said plates has a sliding movement upon the other, the outer plate being stationary with respect to the rule section while the inner plate which is interposed between said outer plate and rule-section being provided with slot 19 has a sliding movement on the pivot pin to separate flanges 21 22 for receiving a section of the zigzag rule between them in connecting the auxiliary rule thereto. Of course the auxiliary rule can be made of several joined sections instead of only two in either instance however the section 13 thereof being of such length with respect to the aforementioned section 12 of the zigzag rule as to equal the length of the sections 10 so that said auxiliary rule section can be placed against the folded zigzag rule section, as shown in Fig. 1 for compactness, and of course it may be held in place by a rubber band or any other securing means.

As will be obvious the attachment will not effect the use of the zigzag rule for ordinary purposes in making measurements, and when it is desired to make inside measurements the auxiliary rule may be readily and quickly applied to any one of the main sections of the zigzag rule by engaging the latter with the metal clip in the manner hereinbefore set forth, and of course said auxiliary rule can be slid along the main rule to any point desired. From this it will be seen that the attachment provides for making inside measurements quickly and accurately, and that it is foldable with the zigzag rule to occupy a minimum amount of space in the mechanic's kit.

65 I claim:

1. An attachment for a carpenter's rule comprising an auxiliary rule and a metal clip pivotally connected thereto for turning movement thereon and consisting of two substantially rectangular plates one slideable with respect to the other, opposing flanges on the plates adapted to clamp the carpenter's rule between them, and a spring interposed between adjoining flanges of the companion plates to move the slideable plate to clamping position. 70
2. An attachment for a carpenter's rule comprising an auxiliary rule and a metal clip pivotally connected thereto for turning movement thereon and consisting of two substantially rectangular plates one slideable with respect to the other, opposing flanges on the plates adapted to clamp the carpenter's rule between them, a spring interposed between adjoining flanges of the companion plates to move the slideable plate to clamping position, and finger engaging portions on the plates for manipulating the slideable plate against the action of the spring. 80
3. An attachment for a carpenter's rule comprising an auxiliary rule and a metal clip pivotally connected thereto for turning movement thereon and consisting of two substantially rectangular plates one slideable with respect to the other, opposing flanges on the plates adapted to clamp the carpenter's rule between them, a spring interposed between adjoining flanges of the companion plates to move the slideable plate to clamping position, and an extension on each plate 90 projecting beyond the rule engaging flange of the companion plate, said extensions having finger engaging portions for manipulating the slideable plate against the action of the spring. 95
4. An attachment for a carpenter's rule comprising an auxiliary rule and a metal clip pivotally connected thereto for turning movement thereon and consisting of a plate pivoted to the auxiliary rule and having a projecting flange, a companion plate slideable on said plate and having a projecting flange cooperating with the aforementioned flange for clamping the carpenter's rule between them, and a spring on one of the plates engaging the other plate to move the slideable plate to clamping position. 105
5. An attachment for a carpenter's rule comprising an auxiliary rule and a metal clip connected thereto and consisting of a plate pivoted to the auxiliary rule for turning movement and having a projecting flange, a companion plate slideable on the aforementioned plate and having outwardly projecting flanges at both sides thereof one of which cooperates with the flange on said first mentioned plate to receive the carpenter's rule between them, and a spring interposed be- 110
6. An attachment for a carpenter's rule comprising an auxiliary rule and a metal clip connected thereto and consisting of a plate pivoted to the auxiliary rule for turning movement and having a projecting flange, a companion plate slideable on the aforementioned plate and having outwardly projecting flanges at both sides thereof one of which cooperates with the flange on said first mentioned plate to receive the carpenter's rule between them, and a spring interposed be- 115
7. An attachment for a carpenter's rule comprising an auxiliary rule and a metal clip connected thereto and consisting of a plate pivoted to the auxiliary rule for turning movement and having a projecting flange, a companion plate slideable on the aforementioned plate and having outwardly projecting flanges at both sides thereof one of which cooperates with the flange on said first mentioned plate to receive the carpenter's rule between them, and a spring interposed be- 120
8. An attachment for a carpenter's rule comprising an auxiliary rule and a metal clip connected thereto and consisting of a plate pivoted to the auxiliary rule for turning movement and having a projecting flange, a companion plate slideable on the aforementioned plate and having outwardly projecting flanges at both sides thereof one of which cooperates with the flange on said first mentioned plate to receive the carpenter's rule between them, and a spring interposed be- 125
9. An attachment for a carpenter's rule comprising an auxiliary rule and a metal clip connected thereto and consisting of a plate pivoted to the auxiliary rule for turning movement and having a projecting flange, a companion plate slideable on the aforementioned plate and having outwardly projecting flanges at both sides thereof one of which cooperates with the flange on said first mentioned plate to receive the carpenter's rule between them, and a spring interposed be- 130

tween flanges of the plates for moving the sliding plate to clamping position.

6. An attachment for a carpenter's rule comprising an auxiliary rule and a metal clip connected thereto for turning movement thereon consisting of a plate pivoted to the auxiliary rule and having a reduced extension at one side thereof with outwardly projecting flanges at the end of said extension
5 and opposite side of the plate respectively, a companion plate slidable between the rule and first mentioned plate and having spaced flanges at one side thereof between which the flanged extension of the other
10 plate projects and an extension at the other side of the slidable plate with an outwardly projecting flange beyond the contiguous flange of said first mentioned plate, and a spring interposed between the last mentioned
15 20 flanges for moving the slidable plate in one direction.
